United States Patent Office

Des. 205,161
Patented June 28, 1966

205,161

INFANT WEIGHING SCALE

Jean O. Reinecke, Glenview, and William Y. Hutchinson,
Chicago, Ill., assignors to Continental Scale Corporation,
Chicago, Ill., a corporation of Delaware

Filed May 7, 1965, Ser. No. 85,171

Term of patent 14 years

(Cl. D52—10)

FIG. 1

FIG. 1 is a front perspective view of an infant weighing scale embodying our new design;

FIG. 2 is a side elevational view thereof; and

FIG. 3 is a rear perspective view thereof.

We claim:

The ornamental design for an infant weighing scale, as shown.
